OIL PILOT DEVICE FOR TRAY TYPE
OIL BURNERS

Kenneth S. Jenson, Wisconsin Rapids, Wis., assignor to Prentiss Wabers Products Co., Wisconsin Rapids, Wis., a corporation of Wisconsin

Application February 11, 1946; Serial No. 646,821

5. Claims. (Cl. 158—91)

1

The present invention relates to improvements in oil pilot devices.

More particularly the present invention relates to improvements in oil burners with particular reference to features thereof relating to the provision of a pilot flame.

An object of the present invention is to provide an oil burner having improved means for delivering air thereto.

A further object is to provide an oil pilot for an oil burner which has the advantage that air for combustion is drawn from a region below the normal oil level in the burner pot through a course of travel which is heated by the pilot flame.

A further object is to provide an improved oil pilot device which is simple and sturdy in construction and certain in operation.

A further object is to provide an improved oil pilot well adapted to meet the needs of ordinary service.

Further objects will appear as the description proceeds.

Referring to the drawings—

Figure 1 is a fragmentary view in section, the section being taken along the plane indicated by the arrows 1—1 of Figure 2;

Figure 2 is a sectional view in elevation, said sectional view being taken along the plane indicated by the arrows 2—2 of Figure 1; and

Figure 3 is a sectional view taken along the plane indicated by the arrows 3—3 of Figure 2.

The bowl portion of a burner is indicated by the numeral 10, said bowl portion having a dished bottom 11 and a vertical annular wall 12, the wall 12 being swaged outwardly a small amount at its upper extremity, as indicated by the numeral 13, for the reception of the cylindrical wall 14 which houses the mixing chamber of the burner. Said cylindrical wall 14 is provided with the usual apertures for admitting air for combustion to said mixing chamber, said holes being indicated by the numerals 15—15. It will be understood, of course, that the burner may be located within a housing of any preferred shape.

The bottom 11 of the burner adjacent to the cylindrical wall 12 is provided with a depressed portion 16 defined by an overflow weir 17. Said depressed portion provides a reservoir for oil or other fuel at a region of the bottom portion 11 adjacent to the cylindrical wall 12. The numeral 18 indicates an oil inlet which may be fed by a supply pipe 19 controlled by a valve 20 which controls the discharge of fuel from the supply pipe 21. The inlet 18 may have its lowermost extrem-

2

ity located slightly above the upper region of the overflow weir 17. The depressed portion 16 is provided with a further depressed portion 22, which provides a sump for holding a small supply of oil or other fuel for providing a pilot flame.

The numeral 23 indicates a housing disposed above the depressed portion 16. Said housing has an opening 24 therein through which oil or other fuel may be admitted from the inlet 18. At the 10 end of the housing distant from the opening 24 is the pilot flame throat 25, this being an opening located adjacent to the bottom 11. Disposed in aligned apertures in the depressed portion 16 of the bottom 11 and in the housing 23 is the pilot 15 air inlet tube 26, approximately vertically disposed, which provides communication from the region below the depressed portion 16 to the region above the housing 23.

Disposed in enveloping relationship with the 20 upper portion of the housing 23 is the enclosure or housing 27, which provides a plenum chamber 28 above the housing 23. The upper wall of the housing 23 is provided with the pilot primary air ports 29—29 and with the pilot secondary air ports 30. The axes of the air ports 29 may be substantially vertical, whereby to direct air more or less directly downwardly into that part of the housing 23 relatively distant from the throat 25. The ports 30 may be directed angularly, whereby air from the plenum chamber 28 will be diverted 25 more directly to the throat 25.

The housing 23 and the enclosure or housing 27 may be welded together and to the cylindrical wall 12, or may be attached by any other preferred means. A bracket 31 may be employed to secure the housing 27 to the wall 14.

In operation, the valve 20 will control the flow 30 of fuel to the burner. Said valve may be either manual or automatic, and in accordance with common practice may be shut completely; may be set to maintain a pool of oil in the sump 22; or may be adjusted to provide any desired oil supply.

Considering conditions when it is desired to 45 maintain a pilot flame within the burner, the valve 20 will be adjusted to maintain a small pool of oil or the like within the sump 22. Combustion of the oil in this sump will maintain the housing 23 and the tube 26, as well as the parts 50 associated with these members, in a heated condition. A flow of air is induced upwardly through the tube 26 from the region below the bottom of the burner to the plenum chamber 28, whence the air will be directed downwardly through the ports 29 and 30 through the throat 25. The mix-

ture of oil and air within the housing 23 provides a combustible mixture burning with a low flame at or adjacent to the throat 25. The transfer of heat from the burning oil in the sump 22 will also produce the advantage that the oil in said sump will be protected against excessive heating so that in the event of cessation of fuel supplied from the pipe 19, the amount of fuel in the sump 22 will not be depleted promptly and fire will be maintained in the sump for a material length of time until the next drop of fuel is admitted from the pipe 19. When a higher fire is required, the flow of oil will be increased through operation of the valve 20. This oil will flow gradually over the weir 11 and will be distributed circumferentially as well as radially into the depressed bottom portion 11. Due to the richness of the mixture within the housing 23 at this time, the pilot flame will be extinguished at the throat 25, the flame being transferred to the fuel in the bottom 11 of the burner. Combustion of the fuel in the bottom 11 may be controlled in the conventional manner by adjustment of the valve 20.

When it is desired to extinguish the flame within the bottom 11, the valve 20 will be throttled to a point where only sufficient oil will be delivered to maintain a small pool within the sump 22. The flame will recede from the bottom 11 of the burner to the throat 25, the reduced richness of the mixture within the housing 23 permitting the maintenance of combustion within the housing 23, thereby maintaining the pilot flame at or adjacent to the throat 25.

Air for combustion for the pilot flame is drawn from the region below the burner to the plenum chamber 28, the air passing through the heated region surrounding the tube 26. Improved control of combustion within the housing 23 is thereby accomplished, resulting in improved certainty of action of the pilot flame.

Though a preferred embodiment of the present invention has been described in detail, many modifications will occur to those skilled in the art. It is intended to cover all such modifications that fall within the scope of the appended claims.

What is claimed is:

1. In a burner, in combination, means providing a combustion chamber having a bottom of dished conformation, means providing a mixture chamber located at one side of said bottom, said last mentioned means having apertures at the top thereof for the admission of air to said mixture chamber, a wall mounted above said last mentioned means and spaced from said last mentioned means to provide a passageway for air to said apertures, a vertically disposed tube extending through said mixture chamber and providing communication for combustion air from a level below said bottom to said passageway, and an oil inlet to said burner at said one side thereof, said bottom being provided with a depressed portion adjacent to said inlet, said depressed portion being defined by a weir for distributing fuel circumferentially and radially into said bottom of dished formation, said depressed portion being further depressed to provide a sump for holding a small supply of fuel, said tube being in thermal communication with said depressed portion.

2. In an oil burner, in combination, means providing a combustion chamber having a dished bottom, a portion adjacent to the edge of said bottom being depressed to provide a reservoir bounded by a liquid fuel distributing weir, said depressed portion at a region adjacent to the

edge of said bottom being further depressed to provide a sump for fuel for a pilot flame, said oil burner being apertured for the delivery of liquid fuel to said depressed portion and said sump, a housing over said depressed portion, said housing having apertures in its upper wall, an enclosure over said housing to provide a plenum chamber communicating with said apertures, and a tube extending through said housing and providing communication for air from a region below said bottom to said plenum chamber, said tube being in thermal communication with said sump.

3. In an oil burner, in combination, means providing a combustion chamber having a dished bottom, a portion adjacent to the edge of said bottom being depressed to provide a reservoir bounded by a liquid fuel distributing weir, said depressed portion at a region adjacent to the edge of said bottom being further depressed to provide a sump for fuel for a pilot flame, said oil burner being apertured for the delivery of liquid fuel to said depressed portion and said sump, a housing over said depressed portion, said housing having apertures in its upper wall, an enclosure over said housing to provide a plenum chamber communicating with said apertures, and a tube extending through said housing and providing communication for air from a region below said bottom to said plenum chamber, said tube being in thermal communication with said sump, said housing having a pilot flame throat directed toward the axis of said burner, certain of said apertures adjacent to the outer periphery of said burner being shaped to direct air approximately vertically downwardly, certain of said apertures closer to the axis of said burner being shaped to direct air downwardly and angularly toward said throat.

4. In an oil burner, in combination, means providing a combustion chamber having a dished bottom, a portion adjacent to the edge of said bottom being depressed to provide a reservoir bounded by a liquid fuel distributing weir, said depressed portion at a region adjacent to the edge of said bottom being further depressed to provide a sump for liquid fuel for a pilot flame, said oil burner being apertured for the delivery of liquid fuel to said depressed portion and said sump, a housing over said depressed portion, said housing having apertures in its upper wall, an enclosure over said housing to provide a plenum chamber communicating with said apertures, and a tube extending through said housing and providing communication of air from a region below said bottom to said plenum chamber, said tube being in thermal communication with said sump.

5. In an oil burner, in combination, means providing a combustion chamber having a dished bottom, a portion adjacent to the edge of said bottom being depressed to provide a reservoir bounded by a liquid fuel distributing weir, said depressed portion at a region adjacent to the edge of said bottom being further depressed to provide a sump for liquid fuel for a pilot flame, said oil burner being apertured for the delivery of liquid fuel to said depressed portion and said sump, a housing over said depressed portion, said housing having apertures in its upper wall, an enclosure over said housing to provide a plenum chamber communicating with said apertures, and a tube extending through said housing and providing communication of air from a region below said bottom to said plenum chamber said tube being in thermal communication with said

sump, said housing having a pilot flame throat directed toward the axis of said burner, certain of said apertures adjacent to the outer periphery of said burner being shaped to direct air approximately vertically downwardly, certain of said apertures closer to the axis of said burner being shaped to direct air downwardly and angularly toward said throat.
